L. O. GRONDAHL

RAILWAY TRAFFIC CONTROLLING APPARATUS

Filed June 11, 1924

Patented May 24, 1927.

UNITED STATES PATENT OFFICE.

LARS O. GRONDAHL, OF PITTSBURGH, PENNSYLVANIA, ASSIGNOR TO THE UNION
SWITCH & SIGNAL COMPANY, OF SWISSVALE, PENNSYLVANIA, A CORPORATION
OF PENNSYLVANIA.

RAILWAY-TRAFFIC-CONTROLLING APPARATUS.

Application filed June 11, 1924. Serial No. 719,332.

My invention relates to railway traffic controlling apparatus, and particularly to apparatus of the type comprising train carried governing mechanism controlled by energy received from the trackway.

I will describe one form and arrangement of traffic controlling apparatus embodying my invention, and will then point out the novel features thereof in claims.

10 The accompanying drawing is a diagrammatic view showing one form and arrangement of railway traffic controlling apparatus embodying my invention.

Referring to this drawing, the reference 15 characters 1 and 1^a designate the track rails of a stretch of railway track over which traffic normally moves in the direction of the arrow. A section A—B of this track is divided from the rest of the stretch by 20 means of insulated joints 2, it being understood that any desired number of such sections may be placed end to end to form a complete system.

Alternating train controlling current is 25 supplied to the rails of the section by a transformer J having a secondary winding 3 constantly connected across the rails adjacent the exit end of the section. The primary 4 of this transformer J is at 30 times supplied with alternating current from some suitable source such as an alternator M. The supply of current to primary 4 may be controlled by any suitable instrumentality, and as here shown this control is accomplished by means of front contact 5 of a track relay R associated with 35 the section in advance of point B. It will be obvious that when relay R is energized, section A—B is supplied with an alternating train controlling current which flows in opposite directions in the two track rails 40 at any instant.

Carried on the train in some convenient location such as in advance of the forward 45 axle of the locomotive are two windings 6 and 6^a in inductive relation with the track rails 1 and 1^a respectively. These two windings 6 and 6^a supply energy to two vibration relays C and D, respectively.

50 Referring particularly to relay C, this relay comprises a core 10 provided with a coil 7, and a polarized armature 11. The left hand end of armature 11 is rigidly fastened to the left hand end of the core 10,

the other end being free to vibrate. Coil 55 7 is connected in series with winding 6 and the circuit is tuned to resonance at the frequency of the current in the track rails by means of a series condenser 8. The armature 11 is tuned to mechanical resonance at the frequency of the current in the track rails by suitably loading the free end with a weight 12 which also serves as a contact, as explained hereinafter. Relay D is similar to relay C and will be 60 understood without further explanation. Coil 7 of relay D is connected with winding 6^a, and the circuit is tuned to resonance at the frequency of the current in the track rails by a condenser 8^a. The two 65 relays C and D are so disposed that the free ends of the two armatures of these relays are adjacent each other, but the parts are so proportioned that when relays C and D are de-energized the weights 12, 12 of the 70 two armatures are separated by a small air gap. If, however, the train occupies a 75 stretch of track which is being supplied with train controlling current the voltage induced in winding 6 causes armature 11 of relay C to vibrate at the frequency of the train controlling current, and similarly, the voltage induced in winding 6^a causes armature 11 of relay D to vibrate at this same 80 frequency. The parts are so proportioned and disposed that for train controlling current which flows in opposite directions in the two track rails at an instant, the armature of relay C is drawn downwardly at the same time the armature of relay D 85 is drawn upwardly. It follows that the weights 12—12 will engage once during each complete vibration. A stop 13 is associated with each armature 11 to prevent the engagement of weights 12—12 should 90 only one relay, C or D be energized.

The weights 12—12 constitute a contact which controls the supply of current from battery 9 to primary 15 of a transformer T. It will be clear from the foregoing that 95 since contact 12—12 is closed once during each cycle of the current applied to the track rails, transformer T is supplied with pulsating direct current of the same frequency. Primary 15 of transformer T is 100 tuned to approximate resonance at the frequency of the current supplied thereto by means of a condenser 14 shunted across this 105

primary. Train governing mechanism of any suitable form and here illustrated as a relay H, is controlled by secondary 16 through the medium of a rectifier G.

5 It will be clear that when the track is supplied with train controlling current, relays C and D are operated to vibrate the associated armatures, and since the relays are so connected that the armatures are 10 attracted simultaneously and repelled simultaneously, contact 12-12 is intermittently closed. The pulsating direct current thus supplied to transformer T causes an alternating current to be induced in secondary 15 16, and this alternating current, rectified by rectifier G, energizes relay H.

One advantage of my invention is that 20 false operation can not be obtained as the result of stray alternating current flowing through the two rails in parallel. In the event of a stray current flowing in this manner, the relays C and D would be energized as before but each armature would then be attracted while the other is being repelled, 25 and so contact 12-12 would not be closed.

Another advantage of my invention is that 30 alternating current in one rail only would energize only one relay and hence contact 12-12 would remain open.

35 Although I have herein shown and described only one form and arrangement of railway traffic controlling apparatus embodying my invention, it is understood that various changes and modifications may be 40 made therein within the scope of the appended claims without departing from the spirit and scope of my invention.

Having thus described my invention, what I claim is:

40 1. In combination, a stretch of railway track, means for at times supplying to said stretch an alternating current which flows in opposite directions in the two track rails at an instant, two train carried windings in inductive relation with the two track rails respectively, two vibration relays receiving energy from said two windings respectively, and train governing mechanism controlled jointly by said relays.

50 2. In combination, a stretch of railway track, means for at times supplying to said stretch an alternating current which flows in opposite directions in the two track rails at an instant, two train carried windings in inductive relation with the two track rails respectively, two vibration relays each comprising an armature tuned to mechanical resonance at the frequency of said alternating current and said relays receiving energy 55 from said two windings respectively, and train governing mechanism controlled jointly by said relays.

60 3. In combination, a stretch of railway track, means for at times supplying to said stretch an alternating current which flows

in opposite directions in the two track rails at an instant, two train carried windings in inductive relation with the two track rails respectively, two vibration relays receiving energy from said two windings respectively, 70 and each comprising an armature which armatures are normally spaced apart but are arranged to be swung periodically into contact when said stretch is supplied with such alternating current, and train governing mechanism controlled by said armatures.

4. In combination, a stretch of railway track, two windings in inductive relation with the two rails of the stretch respectively, two vibration relays receiving energy 80 from said two windings, respectively, and each comprising a vibratable armature having a stop associated therewith to limit the motion of such armature toward the remaining armature, means for at times supplying an alternating current to the rails of the stretch in series to swing said armatures into 85 intermittent contact, and train governing mechanism controlled jointly by said armatures.

5. In combination, a stretch of railway track, means for at times supplying to said stretch an alternating current which flows in opposite directions in the two track rails at an instant, two train carried windings 90 in inductive relation with the two track rails respectively, a first vibration relay included in a circuit containing one of said windings and tuned to approximate resonance at the frequency of said current and comprising an armature tuned to mechanical resonance at the frequency of said current, a second vibration relay included in a circuit containing the remaining said winding and tuned to approximate resonance at the frequency of said current and comprising a second armature tuned to mechanical resonance at the frequency of said current, the relays being so connected with said windings that the armatures are both attracted at the same time and both repelled at the same time and the armatures being so located and proportioned that they engage once during each cycle of said current, and train governing mechanism controlled jointly by said armatures.

6. In combination, a stretch of railway track, means for at times supplying alternating current to the rails of the stretch, two train carried windings in inductive relation with the two track rails respectively, two vibration relays receiving energy from said two windings respectively, and train governing mechanism controlled jointly by said two relays.

7. In combination, a railway, a source of alternating current connected across the track rails thereof, two train carried windings in inductive relation with said two track rails respectively, two relays receiving 130

energy from said two windings respectively, and each including an armature tuned to mechanical resonance at the frequency of said alternating current, train governing mechanism, and means for energizing said mechanism when both of said relays are energized but not when either relay alone is energized.

8. In combination, a railway, a source of alternating current connected across the track rails thereof, two train carried windings in inductive relation with said two track rails respectively, two relays receiving energy from said two windings respectively, and each including an armature tuned to mechanical resonance at the frequency of said alternating current, a contact controlled by said relays and closed when both relays are energized but not when either relay alone is energized, and train governing mechanism controlled by said contact.

9. In combination, a railway, a source of alternating current connected across the track rails thereof, two train carried windings in inductive relation with said two track rails respectively, two relays receiving energy from said two windings respectively, and each including an armature tuned to mechanical resonance at the frequency of said alternating current, and train governing mechanism responding to energization of both of said relays but not to energization of either relay alone.

10. In combination, a railway, a source of alternating current connected across the track rails thereof, two train carried windings in inductive relation with said two track rails respectively, two relays receiving energy from said two windings respectively, and each including an armature tuned to mechanical resonance at the frequency of said alternating current, and train governing mechanism responding to energization of said relays due to an alternating current flowing through said two rails in series but not to energization of said relays due to an alternating current flowing through said two rails in multiple.

11. In combination, a railway, a source of alternating current connected across the track rails thereof, two train carried windings in inductive relation with said two track rails respectively, two relays receiving energy from said two windings respectively, and each including an armature tuned to mechanical resonance at the frequency of said alternating current, a contact controlled by said relays and closed when both relays are energized due to an alternating current flowing through said two rails in series but not when both relays are energized, due to an alternating current flowing through the two rails in multiple, and train governing mechanism controlled by said contact.

In testimony whereof I affix my signature.
LARS O. GRONDAHL.
